This is a continuation-in-part of my application, Serial No. 589,613, filed April 21, 1945, for a drawing implement, and also a continuation-in-part of my application, Serial No. 589,614, filed April 21, 1945, for a drawing implement, both of which are now pending.

UNITED STATES PATENT OFFICE

2,512,492

CURVE FOR DRAWING ELLIPSES

Jack A. Fulton, Ironton, Pa.

Application April 21, 1945, Serial No. 589,613

9 Claims. (Cl. 33—1)

1 This invention relates to drawing implements and more particularly to drawing implements which are adapted to be employed for constructing approximate ellipses.

In the making of drawings, orthographic, axonometric, or perspective, it is frequently necessary to rapidly construct ellipses which are smooth in outline, free from real or apparent distortion, and which are reasonably accurate. Various mechanical devices have heretofore been employed but these are rather complicated in their construction and have not proven wholly satisfactory in use. Various methods of construction have also been employed which include locating a number of points on the ellipse to be drawn, and then connecting the points with curved lines to give an approximation of the desired ellipse. The construction of an ellipse in this manner takes considerable time and is not always satisfactory in shape or appearance.

In accordance with the present invention, a drawing implement is provided which is simple in its construction, may be readily used by unskilled persons, and with which the desired approximate ellipse can be quickly drawn.

In accordance with the present invention, also, a drawing implement is provided with which reasonably accurate ellipses may be readily drawn.

In accordance with the present invention, also, a drawing implement is provided with which approximate ellipses of the desired size can be drawn.

Other advantageous features of the invention will be apparent from the annexed specification and claims.

The nature and characteristic features of the invention will be more readily understood from the following description, taken in connection with the accompanying drawings forming part hereof, in which:

Fig. 1 is a top plan view of one form of drawing implement, in accordance with the present invention;

Fig. 2 is a top plan view of another form of drawing implement, in accordance with the present invention;

Fig. 3 is a diagrammatic view showing the manner of using the drawing implement, in accordance with the present invention;

Fig. 4 is an edge view of the implement shown in Figs. 1 and 2; and

Fig. 5 is a diagrammatic view illustrating the shape and relationship of the various edges of the drawing implement.

It should, of course, be understood that the

drawings illustrate the invention and its construction, and are not intended to be limiting, as the invention may be embodied in other forms. The drawings show a drawing implement having a flat sheet of transparent material, such as a sheet of clear plastic, having a curved edge portion 10, a major axis locus or envelop edge 11, and a center locus line 12. The edge portion 10 is curved and shaped as hereinafter pointed out, a major axis locus or envelop edge 11 is shaped and curved as hereinafter pointed out, and a center locus line 12 thereon of a particular shape, as hereinafter pointed out.

Referring more particularly to the drawings, in which a preferred embodiment of the drawing implement in accordance with the present invention is illustrated, the drawing implement

preferably consists of a flat sheet of transparent material, and preferably of synthetic plastic, having a compound or composite elliptical edge portion 10, curved and shaped as hereinafter pointed out, a major axis locus or envelop edge 11, shaped and curved as hereinafter pointed out, and a center locus line 12 thereon of a particular shape, as hereinafter pointed out.

Referring more particularly to Fig. 5 of the drawings, in which the shape of the drawing implement and the manner of constructing the same are illustrated in detail, the line 15 represents the semi-minor axis and the line 16 represents the semi-major axis, both in one quadrant, of an ellipse, the axis lines 15 and 16 intersecting at a center point 17. The axis lines 15 and 16 terminate at the ellipse at the point 18 and at the point 19 respectively. The portion of the curved edge 10 lying between the point 19 and the point 18 is a true quarter segment of an ellipse and in the embodiment shown the axis lines 15 and 16, and the curve 10 are drawn for an isometric ellipse in which the angle of inclination of the object is of the order of 35°. 16 minutes.

The invention is not, however, limited to these specific ellipses but is adapted for approximate ellipses representing projected views of circles at other angles. The line 20 and the line 21 represent the semi-major and the semi-minor axes respectively, both in one quadrant, of another isometric ellipse of smaller size, and these axes lines intersect at the point 22. The semi-minor axis 20 insofar as can be seen with the eye and within drawing tolerances terminates on the ellipse 19 to 18 at the point 23 and for completing the quadrant of this latter ellipse, an elliptical extension is required below and beyond the point 19 to the terminus 24 of the semi-major axis 21. It has been found that within drawing tolerances and insofar as can be seen with the eye the curve 23 to 24 coincides, in the portion of its length from 23 to 19 with the elliptical curve 18 to 19. The semi-major and semi-minor axes 25 and 26, both in the same quadrant of another isometric

ellipse, are drawn to intersect at the point 27. The axis lines 25 and 26 terminate at the ellipse 19 to 18 at the point 28 and for completing the quadrant of this latter ellipse, an elliptical extension is required below and beyond the point 19 to the terminus 29 of the semi-major axis 26.

The line 30 and the line 31 represent the semi-major and the semi-minor axes respectively, both in one quadrant, of another isometric ellipse of smaller size, and these axes lines intersect at the point 32. The semi-minor axis 30 insofar as can be seen with the eye and within drawing tolerances terminates on the ellipse 19 to 18 at the point 33 and for completing the quadrant of this latter ellipse, an elliptical extension is required below and beyond the point 19 to the terminus 34 of the semi-major axis 31.

It has been found that within drawing tolerances and insofar as can be seen with the eye the curve 33 to 34 coincides, in the portion of its length from 33 to 19 with the elliptical curve 18 to 19. The semi-major and semi-minor axes 35 and 36, both in the same quadrant of another isometric ellipse, are drawn to intersect at the point 37. The axis lines 35 and 36 terminate at the ellipse 19 to 18 at the point 38 and for completing the quadrant of this latter ellipse, an elliptical extension is required below and beyond the point 19 to the terminus 39 of the semi-major axis 35.

ellipse, intersect at the point 27. The minor axis line 25 appears to terminate at the ellipse 18, 23, 19, 24 at the point 28 and an extension of the curve 10 is required beyond the point 24 to the terminus 29 of the semi-major axis 26, to complete the quarter ellipse having the axes 25 and 26. The curve for this latter ellipse appears to coincide for the portion of the line from 28 to 29, with the elliptical curve 23 to 24, and any slight error which may occur may be readily smoothed out.

The curved locus line 12 represents the locus of the centers 17, 22, 27, etc. of the respective ellipses when the ellipses are constructed in apparent superimposed and coinciding relationship as heretofore set forth, and is for a portion of its length apparently of the same shape as the edge 10. The edge 11 is the locus or envelop of the major axes 16, 21, 26, etc. of the ellipses of different sizes brought together as hereinbefore pointed out. The junction of the composite elliptical edge 10 and the edge 11 is preferably rounded off for finishing.

In the form of the invention illustrated in Fig. 1 the edge 10 is provided with suitable scale markings 35, all indicating the size of the circle, as seen in orthographic projection, which will result upon the change of the same to isometric drawing.

In the form of the invention illustrated in Fig. 2 similar graduations 36 are provided along the center locus line 12.

In use, the drawing implement is positioned, as indicated in Fig. 3, with respect to the major axis 40 and the minor axis 41, intersecting at 42, of an ellipse which is to be drawn. The appropriate point scale marking 35 or the scale marking 36, corresponding to the size of the ellipse to be drawn is positioned on the minor axis line 41, above the center 42 if the scale 35 is employed, or at the center 42 if the scale 36 is employed. With the locus line 12 superimposed on the center 42 of the ellipse to be drawn, the major axis envelop edge 11 is then positioned so as to be tangential with respect to the major axis line 40. With the implement thus positioned a line may be drawn with a pencil, ruling pen, or scribe along the elliptically curved edge 10 of the implement and between the axes 40 and 41 a quarter of an apparently accurate ellipse will be provided. The other quarters of the apparently accurate ellipse may then be drawn in a similar manner.

If the outer termini of the major and minor axes 40 and 41 on the ellipse to be drawn are known, the implement may then be positioned with the edge 10 thereon and with the locus line 12 coincident with the center 42 and the quarters drawn in a similar manner.

The largest approximate ellipse which can be drawn is determined by the largest ellipse used in constructing the drawing implement, and the smallest approximate ellipse which may be drawn is the same as the smallest used in the construction. Intermediate sizes of approximate ellipses, between these limits, may be readily drawn.

I claim:

1. An implement for drawing approximate ellipses representing circles of different sizes as projected from the same angle comprising a flat sheet of material having one smooth continuous curved edge portion so shaped that when the implement is placed in various positions quarter segments of approximate ellipses of different selected sizes may be drawn along said edge portion, another edge portion positioned with re-

spect to said edge portion and tangential to the major axes of the approximate ellipses to be drawn, and a locus line disposed between said edge portions and adapted to be positioned at the intersections of the major and minor axes of the respective approximate ellipses to be drawn.

2. An implement for drawing approximate ellipses representing circles of different sizes as projected from the same angle comprising a flat sheet of transparent material having a smooth continuous curved edge portion constructed from the composite of quarter segments of the ellipses to be drawn and adapted, when the implement is placed in various positions, for drawing along said curved edge portion selected quarter segments of said approximate ellipses, another edge portion positioned with respect to said first edge portion and shaped to indicate the envelope of the major axes of the approximate ellipses to be drawn, and a locus line disposed between said edge portions and shaped to indicate the intersection of the major and minor axes of the approximate ellipses to be drawn.

3. An implement for drawing approximate ellipses representing circles of different sizes as projected from the same angle comprising a flat sheet of material having a smooth continuous curved edge portion consisting of a composite of quarter segments of the ellipses to be drawn and adapted, when the implement is placed in various positions, for drawing selected quarter segments of approximate ellipses of different sizes, and another edge portion positioned with respect to said first edge portion and shaped to delineate the envelop of the major axes of the approximate ellipses to be drawn.

4. An instrument for drawing approximate ellipses representing circles of different sizes as projected from the same angle comprising a flat sheet of transparent material having a smooth continuous curved edge portion consisting of a composite of quarter segments of said ellipses adapted, when the implement is placed in various positions, for drawing selected quarter segments of said approximate ellipses, another edge portion shaped to indicate the envelope of the major axes of the approximate ellipses to be drawn, a locus line between said edge portions adapted to indicate the intersection of the major and minor axes of the approximate ellipses to be drawn, and gage markings on said locus line for determining the size of the approximate ellipse to be drawn.

5. An implement for drawing approximate isometric ellipses of different sizes comprising a flat sheet of material having a smooth continuous curved edge portion consisting of a composite of quarter segments of said ellipses to be drawn and adapted, when the implement is placed in various positions, for drawing quarter segments of approximate isometric ellipses of different sizes, another edge portion shaped to indicate the envelope of the major axes of the approximate isometric ellipses to be drawn, and a locus line between said edge portions adapted to indicate the intersection of the major and minor axes of the approximate isometric ellipses to be drawn.

6. An implement for drawing approximate isometric ellipses of different sizes comprising a flat sheet of transparent material having a smooth continuous curved edge portion consisting of a composite of quarter segments of said ellipses adapted, when the implement is placed in various positions, for drawing selected quarter segments of approximate isometric ellipses

of different sizes, another edge portion positioned with respect to said first edge portion and shaped to indicate the envelope of the major axes of the approximate isometric ellipses to be drawn, a locus line on said sheet between said edge portions adapted to indicate the intersection of the major and minor axes of the approximate isometric ellipses to be drawn, and gage markings on said sheet for determining the size of the approximate isometric ellipse to be drawn.

7. An implement for drawing approximate isometric ellipses of different sizes comprising a flat sheet of transparent material having a smooth continuous curved edge consisting of a composite of quarter segments of said ellipses to be drawn and adapted, when the implement is placed in various positions, for drawing quarter segments of approximate isometric ellipses of different sizes, another edge portion positioned with respect to said first edge portion and shaped to indicate the envelope of the major axes of the approximate isometric ellipses to be drawn, a locus line adapted to indicate the intersection of the major and minor axes of the approximate ellipses to be drawn, and gage markings on said first edge portion for determining the size of the approximate ellipse to be drawn.

8. An implement for drawing approximate ellipses representing circles of different sizes as projected from the same angle comprising a flat sheet of transparent material having a smooth continuous curved edge portion consisting of a composite of quarter segments of said ellipses adapted, when the implement is placed in various positions, for drawing selected quarter segments of said approximate ellipses, another edge portion spaced therefrom, a locus line between said edge portions corresponding in curvature to said curved edge portion and upon which the intersection of the major and minor axes of the approximate ellipses to be drawn is adapted to be disposed, and gage lines extending inwardly from said curved edge portion and normal thereto for determining the size of the approximate ellipse to be drawn.

9. An implement for drawing approximate ellipses representing circles of different sizes as projected from the same angle comprising a flat sheet of transparent material having a smooth continuous curved edge portion consisting of a composite of quarter segments of said ellipses adapted, when the implement is placed in various positions, for drawing selected quarter segments of said approximate ellipses, another portion having thereon a locus line corresponding in curvature to said curved edge portion and upon which the intersection of the major and minor axes of the approximate ellipses to be drawn is adapted to be disposed, and gage lines interposed between said curved edge portion and said locus line and normal to said curved edge portion for determining the size of the approximate ellipse to be drawn.
